COMBINATION CIGARETTE DISPENSER, ASH TRAY, AND PENRACK

Edward Hamalainen, Mount Clemens, Mich.

Application March 9, 1949, Serial No. 1,311

Term of patent 7 years

(Cl. D85—2)

To all whom it may concern:

Be it known that I, Edward Hamalainen, a citizen of the United States, residing at 3773 Moran Boulevard, in the city of Mount Clemens, county of Macomb, and State of Michigan, have invented a new, original, and ornamental Design for Combination Cigarette Dispenser, Ash Tray, and Penrack, of which the following is a specification, reference being had to the accompanying drawings, forming part thereof.

The figure is a perspective view of a combination cigarette dispenser, ash tray, and penrack showing my new design. The side not shown is like the one shown and the rear portion is substantially plain.

I claim:

The ornamental design for a combination cigarette dispenser, ash tray, and penrack, as shown and described.

EDWARD HAMALAINEN.
